Attorney.

UNITED STATES PATENT OFFICE.

CLAUDIUS DORNIER, OF FRIEDRICHSHAFEN-ON-THE-BODENSEE, GERMANY, ASSIGNEE
TO THE FIRM: DORNIER METALLBAUTEN GESELLSCHAFT MIT BESCHRÄNKTER
HAFTUNG, OF FRIEDRICHSHAFEN, GERMANY.

FLYING-MACHINE CONSTRUCTION.

Application filed February 7, 1924. Serial No. 691,104.

To all whom it may concern:

Be it known that I, CLAUDIUS DORNIER, a citizen of Germany, residing at Friedrichshafen-on-the-Bodensee, Germany, have invented certain new and useful Improvements Flying-Machine Constructions, of which the following is a specification.

My invention refers to flying machines and more especially to means for connecting the bearing plane or planes with the hull of a flying machine, more especially of the monoplane type. Its particular object is to provide means for connecting and mounting the bearing planes or wings on the hull in a simpler and more efficient manner than has hitherto been possible.

In monoplane or single-deck flying machines of all sorts, including flying boats, the bearing plane or wing has been mounted and fixed on the hull by means of a plurality of rigid struts. However, this mode of fixation cannot be made use of in every case and with all kinds of hulls. Moreover, it entails a number of drawbacks, such as the difficulty resulting from the complicated connection between the plane and the several struts which latter also create a very considerable air resistance.

All these drawbacks are avoided, according to the present invention, by connecting the wing or bearing plane with the hull by means of a single strut disposed in the plane bisecting the wing and in the vertical axial plane of the hull. This strut is fixed to the wing by being attached to or forming part of the wing structure or frame and its free end extends through an opening in the top wall of the hull into the interior thereof, being fastened to the hull preferably in a detachable manner. In a preferred form of this strut its cross-sectional area gradually increases from the point where it is connected or fixed to the hull, up to the point or points where it merges into the wing or bearing plane and the strut will then offer the outward appearance of a funnel. If desired, the end of the strut can be forked in order to properly distribute the joints, more particularly in the case of guide surfaces, tail rudders and the like, where the cross-sectional area of the hull is only small.

In the drawings affixed to this specification and forming part thereof, two flying machines embodying my invention are il-

lustrated diagrammatically by way of example. In the drawings—

Fig. 1 is a front elevation of a wing and hull showing the central position of the strut, while,

Fig. 2 is a side elevation of the machine as a whole.

Fig. 3 is a similar view of a flying boat having the tail rudder connected to the hull by means of a forked axial strut, and

Fig. 4 is a cross-section of the rear portion on the line A—B in Fig. 3.

Referring first to Figs. 1 and 2, *a* is the self-supporting wing of a single-deck flying machine. *c* is the hull and *b* is the single funnel-shaped strut fixed to the wing in a line extending across the wing in the plane bisecting it, the lower end extending deep into a cavity provided in the axial plane of the hull.

In the modification disclosed in Figs. 3 and 4, the rear guide surface or vertical tail rudder *d* is fixed to the rear portion of the hull by means of a single strut *f* forked at the lower part so as to form two arms *g* and *h* which extend into a vertical cavity provided to this end in the rear portion of the hull and in the plane of symmetry.

By thus fixing the wing or rudder to the hull by means of a single strut extending in the plane of symmetry of the hull, the mounting of the wing or rudder is greatly facilitated, so as to require only very little time. The air resistance is diminished very considerably and the transmission of the forces acting on the wing onto the hull are greatly simplified.

I wish it to be understood that I do not desire to be limited to the exact details of construction shown and described, for obvious modifications will occur to a person skilled in the art.

I claim:—

1. The combination, with the hull and the bearing or guide plane of a flying machine, of a single strut fixed to said plane and extending into and being fastened in a cavity provided and extending in the plane of symmetry of said hull.

2. The combination, with the hull and the bearing or guide plane of a flying machine, of a single strut fixed to said plane and forked at its lower end, the forked part of said strut extending into and being fastened

in a cavity provided and extending in the plane of symmetry of said hull.

3. The combination, with the hull and the bearing or guide plane of a flying machine, of a single strut of varying cross-sectional area fixed to said plane and extending into and being fastened in a cavity provided and extending in the plane of symmetry of said hull.

10 4. The combination, with the hull and the bearing or guide plane of a flying machine, of a single funnel-shaped strut fixed to said plane and extending into and being fastened in a cavity provided and extending in the 15 plane of symmetry of said hull.

5. The combination, with the hull and the bearing or guide plane of a flying machine, of a single strut fixed to said plane and extending into and being detachably fastened in a cavity provided and extending in the 20 plane of symmetry of said hull.

6. The combination, with the hull and the bearing or guide plane of a flying machine, of a single funnel-shaped strut fixed to said plane and extending into and being detachably fastened in a cavity provided and extending in the plane of symmetry of said hull.

In testimony whereof I affix my signature,
CLAUDIUS DORNIER.
